HANDRAILING

Wenzel W. Thom, Wichita, Kans., assignor to
Fannie Mae Jones

Filed Aug. 12, 1968, Ser. No. 13,107

Term of patent 14 years

Int. Cl. D25—01

U.S. Cl. D13—7

Fig. 1.

Fig. 3.

Fig. 4.

FIGURE 1 is a perspective view of a handrailing showing my new design;

FIG. 2 is a front elevational view thereof;

FIGS. 3 and 4 are cross-sectional views thereof taken on the lines 3—3 and 4—4 respectively of FIG. 2;

FIG. 5 is an elevational view of one side of one of the posts, showing my new design;

FIG. 6 is an elevational view of another side of the post shown in FIG. 5;

FIG. 7 is a side elevational view of another of the posts, showing my new design, and illustrating the same side thereof shown in FIG. 6; and

FIGS. 8 and 9 are horizontal cross-sectional views taken on the lines 8—8 and 9—9 respectively of FIG. 2.

I claim:

The ornamental design for a handrailing, as shown and described.
